DESIGN FOR A RACK FOR SUPPORTING HYPODERMIC NEEDLES IN CARD FORM

Samuel Galper, Jamaica, N. Y.

Application February 19, 1944, Serial No. 112,637

Term of patent 7 years

(Cl. D83—1)

To all whom it may concern:

Be it known that I, Samuel Galper, a citizen of the United States, residing at Jamaica, in the county of Queens and State of New York, have invented a new, original, and ornamental Design for a Rack for Supporting Hypodermic Needles in Card Form, of which the following is a specification, reference being had to the accompanying drawing, forming part thereof.

In the drawing

Fig. 1 is a perspective view of a rack for supporting hypodermic needles in card form, showing my new design;

Fig. 2 is a side elevational view thereof.

I claim:

The ornamental design for a rack for supporting hypodermic needles in card form, substantially as shown.

SAMUEL GALPER.
